DESIGN FOR AN ELECTRIC SHAVER

Raymond F. Loewy, New York, N. Y., assignor to Schick Incorporated, Stamford, Conn., a corporation of Delaware

Application January 29, 1942, Serial No. 105,510

Term of patent 14 years

To all whom it may concern:

Be it known that I, Raymond F. Loewy, a citizen of the United States, residing at New York, in the county and State of New York, have invented a new, original, and ornamental Design for Electric Shaver, of which the following is a specification, reference being had to the accompanying drawing, forming a part thereof:

Fig. 1 is a front elevational view of a blackout showing my new design;

Fig. 2 a side elevational view; and

Fig. 3 an end elevational view thereof.

I claim:

The ornamental design for an electric shaver, as shown.

RAYMOND F. LOEWY.
